UNITED STATES PATENT OFFICE.

CHARLES ROBERT JONES, OF ROSSVILLE, GEORGIA.

STRAINER ATTACHMENT FOR DRINKING VESSELS.

1,267,417.

Specification of Letters Patent. Patented May 28, 1918.

Application filed November 5, 1917. Serial No. 200,404.

To all whom it may concern:

Be it known that I, CHARLES ROBERT JONES, a citizen of the United States, residing at Rossville, in the county of Walker and State 5 of Georgia, have invented certain new and useful Improvements in Strainer Attachments for Drinking Vessels; and I do declare the following to be a full, clear, and exact description of the invention, such as 10 will enable others skilled in the art to which it appertains to make and use the same.

This invention relates to certain new and useful improvements in straining or filtering 15 devices to be used in connection with drinking vessels or the like.

The principal object of the invention is to provide a strainer which will fit within the upper end of a drinking cup or the like 20 and which will serve to strain or filter water or other liquid as the same is being poured into the vessel and also as it is being poured out of the vessel.

Another object of the invention is to provide 25 a device of this character which will be extremely simple, strong, durable and inexpensive in construction, efficient and reliable in operation and well adapted to the purpose for which it is designed.

With this and other objects in view, the 30 invention consists of certain novel features of construction, and the combination and arrangement of parts as will be hereinafter fully described and claimed.

In the accompanying drawings wherein 35 the preferred form of the invention is shown:

Figure 1 is a perspective view of a well known form of drinking cup, showing a device 40 constructed in accordance with this invention applied thereto;

Fig. 2 is vertical sectional view through the cup, the latter being disposed in a tilted position to show the manner in which the 45 contents of the cup is dispersed from the same during the drinking operation;

Fig. 3 is a front view of the device removed from the cup; and

Fig. 4 is a perspective view of an ordinary 50 table glass showing the device attached to the same.

Referring more particularly to the drawings, the numeral 1 designates an annular rim which fits upon the upper edge of a suitable 55 drinking vessel, which may take the

form of a cup "a" as shown in Figs. 1 and 2 or a table glass "b", shown in Fig. 4. The rim 1 is provided with a comparatively narrow annular depending flange 2 at its outer edge, said flange being adapted to hook 60 around the upper edge of the drinking vessel. The inner edge of the rim 1 is provided with a comparatively wide depending flange 3. The rim is preferably inclined from its outer to its inner edge, and is provided with 65 a mouth opening 4 on one side thereof. Arranged in the flange 3 adjacent to the opening 4 is an opening 5. Fitted over the open lower end of the flange 3 is a cap-shaped member 6 made of suitable straining 70 material, preferably wire screening of very fine mesh. Strips 7 and 8 of the same material are disposed over the openings 4 and 5 respectively, as shown by the drawings. The rim 1 is comparatively narrow and in 75 order to prevent the contents of the vessel from spilling over the inner edge of the rim when the vessel is being tilted to one side, the rim is widened at a point adjacent the opening 4 to form in effect a guard plate 9. 80

When the device is attached to a drinking vessel as shown in the drawings, as water or other liquid is poured into the vessel through the central portion of the device, any sediment or impurities will be collected 85 in the screen cap 6 as the water passes through the same into the bottom of the vessel. When a person desires to drink the contents of the vessel, the latter is tilted toward the opening 4, so that said contents will pass 90 out of the vessel through said opening, and any sediment or impurities which pass through the screen cap 6 will be prevented 95 from passing into the mouth of the person who is drinking by screen strip 8. If the vessel is rather full of water or other liquid a portion of the latter will not pass through the screen cap 6 into the bottom of the vessel but will pass through the screen strip 7 disposed over the opening 5 in flange 3 and thence through the screen strip 8 over the 100 opening 4 in the rim 1.

It is to be understood that the device may be made in various sizes and shapes to fit various forms of drinking vessels, and that it 105 can be made of various materials suitable for the purpose. Numerous other changes in form, proportion, and in the minor details of construction may be resorted to without departing from the spirit of this invention, 110

and hence I do not wish to be limited to the construction herein shown and described other than as claimed.

I claim:

5 1. A straining attachment for drinking vessels comprising a rim adapted to fit upon the upper edge of a vessel and having a mouth opening therein, an annular flange depending from the central portion of said rim, and straining material over said mouth opening and across the lower end of said flange.

10 2. A straining attachment for drinking vessels comprising a rim adapted to fit upon the upper edge of a vessel and having a mouth opening therein, an annular flange depending from the central portion of said rim, a cap-shaped member of straining material fitted upon the lower end of said flange, and a strip of straining material stretched over the mouth opening of said rim.

15 3. A straining attachment for drinking

vessels comprising an annular rim having a narrow flange depending from the outer edge 25 thereof and adapted to hook around the upper edge of a vessel, said rim inclining downwardly from its outer edge to its inner edge and having a mouth opening therein, a comparatively wide annular flange depending 30 from the inner edge of said rim and having an opening therein disposed adjacent to said mouth opening, a cap-shaped member of wire screen fitted upon the lower end of said flange, strips of wire screen stretched over 35 the mouth opening of said rim and the opening in the side of said flange, and a guard plate connected to said rim and disposed adjacent the mouth opening therein.

In testimony whereof I have hereunto set 40 my hand in the presence of two subscribing witnesses.

CHARLES ROBERT JONES.
